UNITED STATES PATENT OFFICE.

JAMES W. G. BECKER, OF KANSAS CITY, MISSOURI, ASSIGNOR TO THE UNITED STATES HEADLIGHT COMPANY, OF BUFFALO, NEW YORK.

ELECTRIC HEADLIGHT.

SPECIFICATION forming part of Letters Patent No. 653,982, dated July 17, 1900.

Application filed April 23, 1900. Serial No. 14,021. (No model.)

To all whom it may concern:

Be it known that I, JAMES W. G. BECKER, a citizen of the United States, residing at Kansas City, in the county of Jackson and State 5 of Missouri, have invented certain new and useful Improvements in Electric Headlights; and I do hereby declare that the following is a full, clear, and exact description of the invention.

10 My invention relates to headlights for electrically-propelled railway-cars, and has for its object improved, efficient, and inexpensive means whereby such headlights can be mounted upon the bumpers of such cars, in 15 front of the dashboards thereof, and whereby the conducting-wires will be protected from the elements.

The invention consists in the construction and arrangement of parts shown in the accompanying drawings, forming a part hereof, and 20 which will be hereinafter fully described, and pointed out in the claims at the end of this specification.

In the said drawings, Figure 1 is a perspective view of a portion of the dashboard and bumper of an electrically-propelled railway-car with my improved headlight mounted thereon. Fig. 2 is an enlarged vertical section through the center line of the headlight. 25 Fig. 3 is a perspective view of the stand detached from the headlight and bumper. Fig. 4 is a modification of Fig. 1. Fig. 5 is a modification of Fig. 3.

A represents the dashboard, and B the bumper, of the car.

C represents the headlight-case, within which is a parabolic reflector D, having a flange e, by which it is secured to the case by screws f. To the front of the case is hinged at 30 c a glass-holder g, containing the usual glass disk h and being held closed by a fastening consisting of the parts i, j, and k in a manner which will be understood without further description. A vertically-movable socket-holder l, having a central bore m, is held by means of a set-screw n in a sleeve o, projecting downwardly from the bottom of and preferably formed integral with the case. The upper end of this holder carries a lamp-socket 35 p, having an incandescent lamp q secured therein and which by means of the said mov-

able socket-holder can be raised or lowered to bring the lamp to proper relation with the horizontal center line of the reflector, which is cut away at k to receive the lamp and its 55 socket.

The case C is preferably made of cast metal and is mounted on a stand I, having a base-plate l, provided with an open space m and uprights n, from which extend flanges o, by 60 which the case and stand are secured together through the medium of bolts or rivets p. The bumper is bored at q, and on the upperside thereof, within the open space m, there is secured a protector or guard J, having a 65 central bore r and which extends up into the lower end of the sleeve F, the latter being enlarged at s to receive the same. Conducting-wires t u lead from underneath the car through the bores r and i to the lamp-socket 70 and are thus protected from the elements. The stand I may have strengthening-webs v and be secured to the bumper by screws or bolts w.

In Fig. 4 of the drawings I have shown the 75 headlight case and stand cast in a single piece, with a vertical portion x serving the function of the sleeve F and protector J and having a central bore y extending from the bottom of the stand into the case, and it is obvious that such construction may be substituted for that shown in Figs. 1, 2, and 3 and hereinbefore described. It is also obvious that the stand may be constructed separate from the case, in the manner shown in Fig. 5, that 80 either of such constructions would come within the scope of my invention, and that other modifications may be made without departing from the spirit thereof.

Having thus fully described my invention, 85 I claim—

1. The combination with the bumper of an electrically-propelled railway-car having a dashboard extending upwardly therefrom, of a headlight-case, a stand therefor adapted to 90 be secured to the bumper, a hollow sleeve communicating with the interior of the case and extending to the bottom of the stand, a vertically-movable socket-holder within said sleeve, and means for securing said stand to 95 said bumper, substantially as shown and described.

2. The combination with the bumper of an electrically-propelled railway-car having a dashboard extending upwardly therefrom, of a headlight-case, a stand therefor adapted to be secured to the bumper, a hollow sleeve communicating with the interior of the case and extending to the bottom of the stand, a vertically-movable hollow socket-holder within said sleeve, a lamp-socket carried by said socket-holder, conducting-wires leading from said lamp-socket through said socket-holder and said sleeve to a source of electric supply, and means for securing said stand to said bumper, substantially as shown and described. 5
3. The combination with the bumper of an electrically-propelled railway-car having a dashboard extending upwardly therefrom, of a headlight-case, a stand upon which it is mounted adapted to be secured to the bumper, 10
- 15
- 20
- 25
- 30
- a hollow sleeve communicating with the interior of the case and extending downwardly from the bottom thereof, a vertically-movable socket-holder within said sleeve, a lamp-socket carried by said socket-holder, a protector or guard secured to the bumper and extending upwardly therefrom into said sleeve, conducting-wires connected with said socket and extending through said socket-holder and said protector or guard to a source of electric supply, and means for securing said stand to said bumper, substantially as shown and described.

In testimony whereof I hereunto subscribe my name this 19th day of April, 1900,

JAMES W. G. BECKER.
